ricated of stainless steel or other thin, light material, extend transversely of the deck sections of each tray for supporting the inner end portions of said sections which are frictionally fastened to the beam by plurality of clamps 21, similar to the clamps 18. The ends of the beam 20 are secured to suitable brackets 22 carried by the wall 10 below the ring 11. It is noted that one end of the tray terminates short of the wall 10 to provide an opening 23 for a weir type downcomer 24 which is secured to and depends from a flange 25 preferably made integral with and extending downwardly and outwardly from the end section 17. An effluent weir 26 is bolted or otherwise fastened to the longitudinal margin of the section 17, while an influent weir 27 is secured to the adjacent longitudinal edge portions of the sections 12 and 13 by their clamps 19.

One longitudinal edge portion of one of the adjacent longitudinal edge portions of the sections is offset downwardly to provide a parallel, co-extensive flange or shoulder 28 which underlies and forms a support for the margin of the adjacent sheet. Each clamp 19 includes a bolt 29 which extends through an opening 30 formed in the flange 28 and has an enlarged washer 31 confined thereupon so as to overlie the adjacent margins of the sections. A nut 32 is screwed onto the lower end of the bolt 29 for clamping the longitudinal edge portion of the overlying section between the flange 28 and the washer 31. With this arrangement, the sections are frictionally fastened together but may undergo limited lateral movement to compensate for thermal expansion and contraction due to temperature changes. If desired, a strip 33 of suitable packing material may be interposed between the flange 28 and the overlying edge portion of the adjacent section. Also, a washer 34 may be confined upon the bolt between the flange and the nut 32. It is noted that each shoulder 28 is of sufficient width to support the overlying edge portion of the adjacent section in unobstructed, spaced relation to the flat portion of the section having said shoulder (Figs. 3 and 7) whereby an expansion joint is provided between adjacent sections and room is provided for the clamp bolts 29 and openings 30.

For reinforcing and adding rigidity to the deck sections so as to eliminate the necessity for use of auxiliary supports, a depending leg or flange 35 may be formed by bending the longitudinal edge portion of each offset portion or flange 28 downwardly at substantially a right angle. Additional rigidity may be obtained by bending the lower extremity of the leg 35 upwardly upon itself to provide a horizontal leg or flange 36 which preferably underlies the flange 28. As shown in Figs. 2 and 7, one longitudinal edge portion of the section 13 is provided with the horizontal flanges 28 and 36 and the depending flange 35, while its opposite edge portion is flat and aligned with the main body of said section. The sections 12 and 15 are flat throughout their areas, the former being supported by the offset flange 28 of the section 13 and the latter having its longitudinal edge portions supported by the offset, horizontal flanges formed on the adjacent margins of the sections 14 and 16. Both longitudinal edge portions of these sections are provided with the offset flanges for supporting the adjacent overlying margins of the sections 13 and 17.

It is pointed out that this particular construction and arrangement of the sections are not

essential or necessarily desirable, being subject to variation due to the location, strength and dimensions of said sections as well as the load placed thereupon and the function of the tray. 5 In some installations, each section will have only one offset, flanged longitudinal edge portion. Ordinarily, the depending flange 35 and horizontal leg 36 will be incorporated with each offset flange 28. If desired, an elongate flat plate or bar 37 may be welded or otherwise secured to each of the depending flanges 35 so as to add rigidity thereto and additionally reinforce the same. This bar is preferably formed of similar material, but is of heavier gauge or greater thickness.

In order for the end portions of the sections to overlie the ring 11, the offset flange 28, its depending flange 35 and horizontal leg 36 are of less length than said sections so as to terminate 20 short of said end portions as shown in Figs. 3 and 4. A clamp 38 is provided for frictionally fastening the connected adjacent margins of the sections to the ring and includes an elongate, 25 flat plate or clamping member 39 which overlies and extends longitudinally of said adjacent margins. An opening 40 is formed in the plate 39 for receiving a bolt 41 which extends through an opening 42 formed in the offset flange 28 of the underlying section and has an angular member or plate 43 secured on its lower end by a suitable nut (not shown). The plate 43 underlies the ring 11 and has an upstanding, transverse lug 44 at its inner end for bearing against the underside of the offset flange 28. Due to this arrangement, 35 the adjacent margins of the sections are clamped to the ring between the plates 39 and 43.

The tray preferably includes a manway 45 which may be at any desired point but which has been shown between the portions or sub-sections 15a and 15b of the section 15. The longitudinal margins of the manway 45 extend parallel to the longitudinal edges of the sub-sections 15a and 15b so as to overlie the offset flanges 28 of the sections 14 and 16. For supporting the 45 end portions of the manway, the adjacent end portions of the sub-sections 15a and 15b are provided with downwardly offset flanges 46 which may be reinforced by depending flanges 47 and horizontal legs 48 as well as by bars 49, similar to the flange 35, leg 36 and bar 37.

A plurality of clamps 50 are provided for detachably securing the manway to the flanges 28 and 46, and each clamp includes a cylindrical stud or pin 51 having a circular washer 52 welded or otherwise secured thereto adjacent its lower end. The stud 51 projects upwardly through an opening 53 formed in the offset flange 46 with its washer 52 bearing against the underside of said flange. A horizontal clamping member or angle bar 54, is welded or otherwise secured to one side of the stud 51 adjacent its upper end, and extending at a right angle to the axis of said stud and being of sufficient length to overlie the marginal edge portions of the manway and adjacent section or sub-section. As shown by the numeral 55, the ends of the clamp member are bent upwardly to provide a clearance lip which will ride upon and over the margin of the manway. It is noted that the space between the washer and the clamping member is only sufficient to permit turning of the stud by a wrench or other tool (not shown). If desired, a strip 56 of suitable packing is interposed 70 between the margins of the manway and the offset flanges 46 as well as the flanges 28.

It is manifest that a quarter turn of the stud is sufficient to move the clamping member from a latched to an unlatched position, the upturned ends or lips 55 of said member riding over and clamping the margin of the manway into snug engagement with the offset flange. When the clamp is latched, the bar overlies the margins of the manway and section or sub-section. Upon turning the clamp to its unfastened position, the bar is swung clear of the manway and overlies only the margin of the section or sub-section whereby the manway may be readily removed. A broad bearing surface is provided by the washer 52 due to its enlarged diameter. The clamp is not only simple in construction but eliminates the necessity of using bolts and nuts without the danger of the manway becoming loose due to vibration.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A refining vessel tray including, a deck having a plurality of elongate sections supported at their ends and disposed within their longitudinal edge portions in adjacent substantially parallel relationship, at least one of the longitudinal edge portions of at least one of the sections being offset downwardly, the longitudinal edge portion of an adjacent section resting upon and supported by said offset edge portion in coplanar relationship, means carried by said offset edge portion in transversely spaced relation to the supported edge portion and overlying the latter edge portion for frictionally fastening together the edge portions, the offset edge portion being bent downwardly to form a supporting flange for said edge portions, said deck section and offset edge portion and supporting flange being formed integrally from one sheet to provide a one-piece structure, said offset edge portion having openings therein, the fastening means including studs in the openings, washers on the studs beneath the deck sections, and a clamping bar at and secured to one side of each stud and extending at a right angle to the longitudinal axis thereof, the bar being spaced from the washer a distance approximately equal to the thickness of the adjacent section.

2. In a refining vessel tray, a one-piece tray section comprising an elongate one-piece plate and reinforcing support of light gauge metal, the plate having a substantially flat major portion with one of its longitudinal edge portions offset downwardly a distance substantially equal to the thickness of the plate to provide an offset horizontal shoulder for supporting the flat longitudinal edge portion of an adjacent tray section in coplanar relation to the substantially flat major portion of said plate, the support being formed by an integral flange depending from the outer edge portion of the offset shoulder, the flange reinforcing said plate and supporting the edge portion of the tray section seated upon said shoulder, said offset shoulder being of sufficient width to provide an unobstructed spaced relationship between the seated edge portion of the tray section and said substantially flat major plate portion so as to permit lateral thermal expansion and contraction of the tray section and plate.

3. A one-piece section as set forth in claim 2 wherein the plate has both of its longitudinal edge portions offset downwardly to provide a pair of offset horizontal shoulders.

4. A one-piece tray section as set forth in claim 2 including frictional fasteners carried by the unobstructed portion of the shoulder in spaced relation to the seated edge portion of the adjacent tray section for overlying the seated edge portion to clamp the tray section against upward displacement relative to the plate.

HANS C. GLITSCH.
